UNITED STATES PATENT OFFICE.

CAMILLE JEAN HAUTIER, OF BOULOGNE-SUR-SEINE, FRANCE.

INTERNAL-COMBUSTION ENGINE.

1,243,835.

Specification of Letters Patent. Patented Oct. 23, 1917.

Application filed December 1, 1913. Serial No. 803,957.

To all whom it may concern:

Be it known that I, CAMILLE JEAN HAUTIER, citizen of the Republic of France, resident of 58 Rue du Chateau, Boulogne-sur-5 Seine, Seine, in the said Republic, engineer, have invented certain new and useful Improvements in Internal-Combustion Engines; and I do hereby declare the following to be a full, clear, and exact description of 10 the invention, such as will enable others skilled in the art to which it appertains to make and use the same, reference being had to the accompanying drawings, and to letters or figures of reference marked thereon, 15 which form a part of this specification.

This invention relates to distributing devices for internal combustion engines and consists in using a single distributor moved parallel to the axis of the cylinder and having 20 ducts adapted to coöperate with suitable ports in the wall of the cylinder between the two ends of the stroke of the piston, so as to admit into the cylinder at each suction stroke a charge of fresh gas and at the same time a 25 complementary and variable proportion of burnt gases in order that the volume admitted into the cylinder may be kept always constant whatever the quantity of the fresh gas admitted, and in order that the ignition 30 of this fresh gas may be facilitated by reason of the temperature which it acquires from the hot gases wherewith it is intimately 35 mixed. The distributor consists of a cylindrical slide having rectilinear movement and rendered tight by packing rings, the width of which is proportional to the stroke of the slide; it is mounted so that its axis does not 40 cut the axis of its controlling shaft, so that at periods corresponding with the compression, explosion and the greater part of the 45 expansion, the exhaust port is completely covered by the corresponding packing ring.

The method of distribution is applicable both to four-stroke cycle and to two-stroke 45 cycle internal combustion engines, the controlling shaft of the distributing slide being driven in the first case at half the speed of the crank shaft and in the second case at the same speed as this shaft.

50 The accompanying drawing shows by way of example in Figures 1-4 diagrammatic sections through the axis of the working cylinder of a four-stroke internal combustion engine having a distributor according to the 55 invention.

Figs. 1, 2 and 3 show the position of the parts at the beginning of the suction stroke, at the beginning of the compression stroke and at the beginning of the working stroke respectively. Fig. 4 shows the distributor 60 slide displaced relatively to the working piston which is in an intermediate position so as to increase the proportion of burnt gases which is sucked back into the cylinder, thereby diminishing the quantity of fresh 65 gas admitted. Fig. 5 is a side elevation partly diagrammatic and drawn to an enlarged scale of the sleeve which when shifted on the distributing shaft determines the displacement of the distributing slide. 70

The working cylinder *a*, in which moves the piston *b*, is provided with two lateral ports *c* and *d* adapted respectively for the admission and the exhaust and situated between the two ends of the stroke of the piston *b*, the admission port *c* being for example as shown in the drawing at two-thirds of the stroke of the piston. *e* is the crank shaft and *f* a connecting rod between the piston *b* and this shaft. 75

At that side of the cylinder *a* in which the ports *c* and *d* are situated there is a cylindrical guide *g* for the distributing slide. The latter is an open ended cylinder subdivided internally by two partitions *i*, *j*; the chamber between these partitions has lateral admission ports *k* intended to register with the admission port *c* of cylinder *a*. Above the upper partition *i* the cylindrical slide has a lateral port *l* intended to register with the port *d* of the cylinder *a* so as to put the latter into communication with the exhaust through pipe *m* which forms an extension of the cylindrical guide *g*. The admission duct *n* for fresh gas opens into the cylindrical 85 guide *g* at a point substantially in line with the admission port *c* of cylinder *a*. The distributing slide is rendered tight by packing rings *o* of considerable width which slide 90 is in contact with the admission and exhaust ports *c*, *d* of the cylinder. 95

The distributing slide is driven by a shaft *p* turning at one half the speed of the crank shaft *e* with which it is in gear through a suitable train *q*; the shaft *p* is mounted 105 with its axis out of the axial line of the distributing slide and a connecting rod *r* connects it with the slide.

Owing to this axial displacement the movement of the slide is not uniform but is 110

first accelerated and then retarded so as to obtain the desired relative displacement in respect of the ports of the cylinder. The control would also be through an eccentric, 5 a cam or like device suitably mounted on the distributing shaft p . The latter consists of two parts p , p' (Fig. 5) co-axial with each other and surrounded at their adjacent ends by a sliding sleeve s . This 10 sleeve has a rectilinear groove t engaging a straight feather u on the portion p of the shaft, and a helical groove v engaging a feather of like form w on the portion p' of the shaft. By means of a collar x on the 15 sleeve s the latter can be easily displaced. It will be seen that axial movement of the sleeve on the shaft will rotate part p thereof relatively to part p' , thus changing the angular position of the distributor shaft 20 with respect to the motor shaft and displacing the distributor slide h relatively to the working piston b .

The arrangement operates as follows:—

When piston b is at the upper end of its 25 stroke, as shown in Fig. 1, and is about to descend to perform the suction stroke, the admission and exhaust ports c and d of the cylinder are closed by the packing rings o of the downwardly moving distributing 30 slide. As the piston and distributor continue their downstroke the lower packing ring of the distributor uncovers the admission port c and owing to the slower movement of the distributor fresh gas is drawn 35 into the cylinder through n and k from the time the piston uncovers the port c until the piston reaches the end of its down stroke, as shown in Fig. 2.

When the piston begins the compression 40 stroke, the ports c , k , n , are in register, and a part of gas drawn in on the suction stroke is returned through the admission port c , which remains open so that only the charge 45 remaining between this port and the end of the cylinder constitutes the maximum volume of fresh gas taken into the cylinder. When the piston covers the port c the fresh 50 gases are compressed as shown in Fig. 3. At the moment of the explosion the packing rings o and the piston b cover completely the ports c and d as well as during 55 the whole period which precedes the advanced exhaust.

Fig. 4 shows the displaced position of the 55 distributing slide relatively to that of the working piston, the displacement having been effected during the suction stroke by means of the sliding sleeve s (Fig. 5). The slide and the piston occupy this position at 60 the beginning of the suction stroke, the port l of the distributing slide has come into registration with the exhaust port d of the cylinder a and owing to the angular displacement of the shaft p with respect to the motor shaft e , said port l remains more

or less in registration with port d during a part of this period. The volume admitted consists only in part of the fresh gases, being completed by the hot burnt gases so that the compression remains constant and 70 combustion is facilitated and more complete.

I claim:—

1. In an internal combustion engine, a working cylinder having inlet and exhaust ports therein, a working piston in the cylinder controlling said ports, an exhaust conduit arranged to communicate with the exhaust port, a controlling member for said ports having a fuel chamber adapted to communicate with the inlet port, and means 80 to actuate the controlling member so as to supply to the cylinder burnt gases from the exhaust conduit and fuel from said chamber during the suction stroke of the piston and to return part of said fuel to the chamber during the compression stroke of the piston.

2. In an internal combustion engine, a working cylinder having inlet and exhaust ports therein, a working piston in the cylinder controlling said ports, an exhaust conduit arranged to communicate with the exhaust port, an admission conduit, a slide adapted to control said ports and conduit and having ports arranged to connect the admission conduit with said inlet port, and means to actuate the slide to connect the exhaust port with the exhaust conduit and connect the admission conduit with the inlet port during the suction stroke of the piston 100 and to maintain the connection between the admission port and admission conduit during a portion of the compression stroke of the piston.

3. In an internal combustion engine, the 105 combination of a working cylinder having an exhaust port near its upper end and an admission port below the exhaust port, a piston, a crank shaft, a driving connection between said crank shaft and piston, a cylindrical guide parallel to the axis of said working cylinder, a single distributor slide in said guide, a distributing shaft, means to actuate said slide from said distributing shaft, an admission conduit intermediate the 110 ends of said guide, an exhaust conduit communicating with the upper end of said guide, said distributor having an admission port intermediate its ends coöperating with the admission conduit and admission port of 115 said cylinder and an exhaust port coöperating with the exhaust port of said cylinder and said exhaust conduit, and means to angularly adjust the distributor shaft with respect to the crank shaft during the operation of the piston to connect the exhaust port with the exhaust conduit and connect the admission conduit with the inlet port during the suction stroke of the piston and to maintain the connection between the ad- 120

mission port and admission conduit during a portion of the compression stroke of the piston.

4. In an internal combustion motor, a cylinder having an exhaust port near its upper end and a separate inlet port below the exhaust port, a piston in said cylinder controlling said ports, a crank shaft, a driving connection between said crank shaft and piston, a ton, a cylindrical guide parallel with said cylinder, a single piston distributor in said cylindrical guide, a distributing shaft displaced with respect to the axis of said guide and distributor, driving means between said shaft and distributor, an admission conduit intermediate the ends of said guide, an exhaust conduit at the upper end of said guide, a port intermediate the ends of said distributor coöperating with and controlling said inlet conduit and inlet port, a port in the upper portion of said distributor to control communication between said exhaust port and exhaust conduit, and means to angularly displace the distributor shaft with respect to the crank shaft during the operation of the piston to connect the exhaust port with the exhaust conduit and connect the admission conduit with the inlet port during the suction stroke of the piston and to maintain the connection between the admission port and admission conduit during a portion of the compression stroke of the piston.

5. In an internal combustion motor, a cylinder having an exhaust port near its upper end and a separate inlet port below the latter, a piston in said cylinder controlling said ports, a crank shaft, a driving connection between said piston and crank shaft, a cylindrical guide parallel with said cylinder, an inlet pipe intermediate the ends of said guide and an exhaust pipe at the top of said guide, a single hollow piston distributor in said guide for controlling said ports and having a chamber provided with inlet and outlet ports, said ports and chamber controlling communication between the inlet pipe and the inlet port of said cylinder, said distributor also having a port above said chamber controlling communication between the exhaust port of the cylinder and the exhaust pipe, and means to actuate said distributor during the operation of the piston to connect the exhaust port with the exhaust conduit and connect the admission conduit with the inlet port during the suction stroke of the piston and to maintain the con-

nexion between the admission port and admission conduit during a portion of the compression stroke of the piston.

6. In an internal combustion engine, the combination of a working cylinder having an exhaust port near its upper end, and a separate inlet port below said exhaust port, a piston in said cylinder controlling said ports, a crank shaft, a driving connection between said piston and shaft, a cylindrical guide parallel with said cylinder, a single distributor piston having two ports controlling the ports in the cylinder, a distributor actuating shaft out of alinement with the axis of the distributor, means to drive said shaft from said crank shaft, and means to angularly displace the distributor shaft to adjust the relative movement of said distributor with respect to said piston during the operation of the piston to connect the exhaust port with the exhaust conduit and connect the admission conduit with the inlet port during the suction stroke of the piston and to maintain the connection between the admission port and admission conduit during a portion of the compression stroke of the piston.

7. In an internal combustion engine, the combination of a working cylinder and its piston, a crank shaft, a connecting rod between the said piston and shaft, a cylindrical guide parallel to the axis of the working cylinder, a distributing piston adapted to move in the said cylindrical guide, a distributing shaft in two parts, means for connecting these two parts and causing one of them to turn relatively to the other for the purpose of displacing the distributing piston relatively to the working piston, a connecting rod between the distributing piston and one of the portions of the said distributing shaft, ports adapted to open communication between the working cylinder and the cylindrical guide, an admission pipe and an exhaust pipe opening into the said guide and ports formed in the distributing piston for putting in communication the said ports in the working cylinder with the said pipes.

In testimony that I claim the foregoing as my invention, I have signed my name in presence of two subscribing witnesses.

CAMILLE JEAN HAUTIER.
